Specification for Design.

Patented Jan. 17, 1922.

Application filed February 21, 1921. Serial No. 446,967. Term of patent 14 years.

To all whom it may concern:

Be it known that I, ANDREW SANDEGREN, a citizen of the United States, residing at Chicago, in the county of Cook and State of Illinois, have invented a new, original, and ornamental Design for a Bathtub, of which the following is a specification, reference being had to the accompanying drawing, forming part thereof.

Figure 1 is a perspective view of a bath tub embodying my design.

Figure 2 is a reduced plan view thereof. These views show a tub of pleasing design, especially with reference to its interior arrangements and outlines, adapted for bathing in a sitting or upright position and including both a large and a small tub for an adult or a child, respectively.

I claim:

The ornamental design for a bath tub, as

ANDREW SANDEGREN.
